Primary Examiner — Marianne Pandozzi*Assistant Examiner* — Brett Miller(74) *Attorney, Agent, or Firm* — Scherrer Patent & Trademark Law, P.C.; Stephen T. Scherrer; Monique A. Morneau(57) **CLAIM**

The ornamental design for a protective cover for conduit, as shown and described.

DESCRIPTION

FIG. 1 is a front top perspective view of a protective cover for conduit;

FIG. 2 is bottom perspective view of a protective cover for conduit;

FIG. 3 is a top view of a protective cover for conduit;

FIG. 4 is a bottom view of a protective cover for conduit;

FIG. 5 is a right side and a left side view of a protective cover for conduit, said right side and left side views being identical; and,

FIG. 6 is a front and rear view of a protective cover for conduit, said front and rear views being identical.

The broken lines depict unclaimed environmental subject matter.

1 Claim, 3 Drawing Sheets(56)
